(57) CLAIM

The ornamental design for a universal carrying device, as shown and described.

DESCRIPTION

FIG. 1 is a perspective view of a universal carrying device; FIG. 2 is a side elevation view thereof, the sides being mirror images of each other;

FIG. 3 is a front elevation view thereof;

FIG. 4 is a rear elevation view thereof;

FIG. 5 is a top plan view thereof;

FIG. 6 is a bottom view thereof;

FIG. 7 is a perspective view of a universal carrying device holding a broken line drawing of a bottle for illustrative purposes only, where the broken line drawing forms no part of the claimed design; and,

FIG. 8 is a perspective view of a universal carrying device held inside a broken line drawing of a waist band or belt worn by a human, whereas a broken line drawing of a bottle is being carried by the universal carrying device for illustrative purposes only, where broken line drawings form no part of the claimed design.
